SAFETY WRENCH

Arthur L. Parker, Cleveland, Ohio, assignor to The Parker Appliance Company, Cleveland, Ohio, a corporation of Ohio

Application March 27, 1943, Serial No. 480,806

5 Claims. (Cl. 81—177)

The invention relates to new and useful improvements in a safety wrench adapted for use in turning bolts, nuts, and coupling elements or the like, hereinafter referred to as a part.

It is well known that by applying excessive pressure to a wrench for turning a part, such as a bolt or nut, that often the threads are stripped, also that when excessive pressure is applied to the wrench for tightening a tube coupling, the end of the tube is pinched off within the coupling. Such unseen damage jeopardizes expensive equipment and human lives. It is the purpose of the present invention to provide a safety wrench which is so constructed that the operator using the same will be warned when the pressure applied to the wrench is excessive and likely to damage the parts.

An object of the invention is to provide a safety wrench having a handle, a portion of which is grasped within the hand of the operator, which handle is so constructed that the operator through the feel of the hand will be warned when the pressure approaches an excessive pressure which might disrupt and injure the parts.

A further object of the invention is to provide a safety wrench of the above type, wherein the handle portion grasped by the operator is so dimensioned that the portion thereof within the grip of the hand will flex under pressure, and thus the operator may determine through the feel of the hand the approximate pressure being applied to the wrench for the turning of the part to which it is attached.

Another object of the invention is to provide a safety wrench of the above type which is provided with means for varying the flexibility of the portion of the handle within the grip of the hand of the operator, so that greater or less pressure is necessary for flexing the same to a given extent.

These and other objects will in part be obvious and will in part be hereinafter more fully disclosed.

In the drawing.

Figure 1 is a plan view of a safety wrench embodying the improvements, also showing in broken lines the flexing of the handle when pressure is applied for turning a part.

Figure 2 is a side view of the same, with parts of the head in section.

Figure 3 is a sectional view on the line A—A of Figure 2.

Figure 4 is a view of the head end of the wrench, similar to Figure 2, but showing a modified means for joining the handle to the wrench head.

Figure 5 is a side view of a modified form of handle for the improved safety wrench.

Figure 6 is a side view of a further modified form of handle for the safety wrench.

The safety wrench embodying the invention includes a head 1 having a socket 2 adapted to be attached to the part which is to be turned. There is an opening 3 leading to the socket so that the wrench can be conveniently applied to a coupling element associated with a tube or pipe. The socket head is shaped so as to provide surfaces conforming to the hexagonal shape of the nut to which it is to be applied so that when the socket is placed over a nut or bolt head, the wrench head will be so attached to the part to be turned that said part will turn with the head and not in the socket of the head.

Attached to the head 1 is a handle 4. The portion of the handle between the point 5 and the end 6 is to be grasped within the hand of the operator for the turning of the part. The handle 4 is provided with a longitudinal slot 7, in one wall of which is a semi-circular recess 8 and in the other wall of which is a semi-circular recess 9. The head 1 of the safety wrench is slotted, as indicated at 10, and mounted in said head and extending across the slots are pins 11 and 12. The handle may be detached from the head by turning the handle relative to the head so as to move the pins 11 and 12 out of the recesses 9 and 8, respectively. The handle may then be moved lengthwise for disconnecting it from the head.

The slot 10 lies in the plane of the handle and this plane is parallel to the axis of the socket in the wrench head. Pressure is applied to the side face of the handle for the turning of the part to which the wrench is attached, and this turning torque is against the side walls of the slot. The handle is made of spring metal and is of greater thickness at the wrench head than at the outer end thereof, as shown in Figures 1 to 4. Said handle tapers uniformly from the maximum thickness at the wrench head to the outer end thereof. When the operator grasps the outer end portion of the handle and applies pressure thereto for turning the wrench the part to which it is attached, the handle will flex, as indicated in broken lines in Figure 1. It will be apparent that the outer end portion of the handle which is of less thickness will flex to a greater extent than the portion of the handle between the point 5 and the wrench head. This enables the operator through the feel of the hand and through the extent of the flexing of the end of the wrench

handle to determine approximately the pressure applied to the turning of the part. The parts are dimensioned so that the wrench handle will flex to the position indicated in the drawing when the nut or part being turned is brought to a proper tightness without damaging the threads or the parts being clamped.

The handle as shown in Fig. 2 is provided with parallel slots 13 and 14 which extend from a point adjacent the outer end 6 of the handle to a point near the head 1 and terminate in a recess 15. These slots provide a tongue 16 which is integral with the outer end of the handle and is free from connection with the handle at its inner end. Mounted on the handle are two flat rectangular plates 17 and 18. These plates are connected by a U-shaped holding device 19 which extends through the slots and are bent back onto the outer face of the lower plate, as shown in Figure 3, and thus the plates are caused to grip the handle and remain in a fixed position thereon. These plates may be shifted along the tongue and wherever it is placed, it will limit the flexing of the tongue so that the portion of the tongue between the plates and the outer end of the handle will flex with the handle, while the portion of the tongue between the plates and the wrench head will not be flexed, but will move out of the slot in the handle unrestrained. By the shifting of these plates along the handle the flexibility of the handle can be increased or decreased. When the plates are moved toward the outer end of the handle, then the flexibility of the handle between the plates and the wrench head is solely in the main handle. If these plates be shifted up close to the head, then to the pressure necessary to flex the handle is added a pressure necessary to flex the tongue 16. When the wrench is to be used in connection with parts to be tightened which will stand a greater torque without damage, the plates will be shifted toward the wrench head and this will require a greater pressure before the handle will flex to an extent roughly indicated by the dotted lines in Figure 1.

While the exact pressure applied to the handle for tightening the part cannot be accurately and mathematically determined by the feel of the hand, yet an operator can determine approximately the tightness to which a part is turned and thus be assured that wrench pressure is not being applied to an extent to damage or weaken any of the parts.

In Figure 4 the wrench head 1 is of the same construction as shown in Figures 1 and 2. Likewise the handle 4 is of the same construction. The means for securing the handle to the wrench head is slightly different. Instead of providing a detachable connection as shown in Figures 1 and 2, the handle is secured between the walls of the wrench head by rivets or bolts 19, and thus the handle is rigidly and permanently attached to the wrench head.

In Figure 5 the wrench head is of the construction shown in Figures 1 and 2 and is attached to the handle 20 by rivets or bolts 19, 19 so that the handle is rigidly and permanently attached to the wrench head. The handle as shown in Figure 5 is of uniform thickness. The handle is of uniform width from the wrench head to substantially the line x-x and from this line to the end of the handle it tapers down to a relatively small end portion, as indicated at 21. In view of this dimensioning of the handle so that it is of less width in the portion which is grasped by the hand of the operator, the end

portion within the grasp of the hand will flex when pressure is applied to the wrench in the manner described in connection with Figures 1 and 2, and here again the operator will, through the feel of the hand, be able to determine the approximate pressure applied to the tightening of the part and therefore will avoid excessive wrench pressure which would be likely to damage the parts being tightened.

In Figure 6, the wrench head 1 is of the same construction as in Figures 1 and 2 and is secured rigidly and permanently to the handle 22 by means of rivets or bolts 19, 19. In this form of the invention the handle 22 is of uniform width from the wrench head to the outer end 23 and at the outer end is substantially semi-circular. The handle is cut away as indicated at 24. The recess formed by the cutting away of the handle is smaller at the inner end 25 and larger at the outer end 26. This will so dimension the metal of the handle that the outer end portion grasped in the hand of the operator will flex when turning torque is applied to the wrench in the manner described in connection with Figures 1 and 2. This will enable the operator through the feel of the hand to determine the approximate wrench pressure which is applied to the turning of the part to which the wrench is attached and avoid excessive pressure which might damage the parts.

The handle is described above as detachably connected to the wrench head. This enables a handle dimensioned for easy flexing to be removed and a substitute handle attached which is not so easily flexed, where it is desired to use the wrench on parts to which a greater turning torque may be applied without injuring the same. It is obvious that many ways may be employed of detachably connecting the handle of the wrench head and only one simple means has been illustrated.

As previously stated, flexing or yielding of the wrench handle within the operator's hand provides a sensible signal to warn the operator against further tightening of the part. Actual tests with this wrench indicate that even inexperienced operators will invariably tighten parts to within a permissible range of tightness. Obviously, as a further precaution against overtightening and consequent damage to parts, the handle can be constructed so as to break or snap in two when the upper limit of the range of suitable torques has been seriously exceeded. This would serve as an added precaution against overtightening of parts by inattentive or unscrupulous operators who fail to heed the warning given by the flexing of the handle within the hand.

It is obvious that many changes in the shaping of the parts and the dimensioning of the same may be made without departing from the spirit of the invention as set forth in the appended claims. It is essential, however, that the handle shall be of a material which will be flexed within the pressure necessary to turn a nut or a part to which the wrench is attached to a proper degree of tightness. It is also essential that the flexibility of the handle in the portion thereof grasped by the hand of the operator shall be greater than the portion of the handle adjacent the head, so that the operator through the feel of the hand, may approximate the pressure which is applied to the wrench for the turning of the part.

I claim:

1. A safety wrench comprising a head having means adapted for engagement with a part for turning the same, an operating handle rigidly connected to said head and extending outwardly therefrom, the outer end portion of the handle which is adapted to be grasped by the hand of the operator for turning the part being relatively wide and sufficiently thin as to flex within the hand of the operator when pressure is applied to the handle for turning the part whereby the extent of flexibility of the portion grasped by the hand may be utilized for determining the approximate tightness of the part being turned.

2. A safety wrench comprising a head having means adapted for engagement with a part for turning the same, an operating handle rigidly connected to said head and extending outwardly therefrom, the outer end portion of the handle which is adapted to be grasped by the hand of the operator for turning the part being relatively wide and sufficiently thin as to flex within the hand of the operator when pressure is applied to the handle for turning the part and means for varying the flexibility of the handle, whereby the extent of flexibility of the portion grasped by the hand may be utilized for determining the approximate tightness of the part being turned.

3. A safety wrench comprising a head and a means adapted for engagement with a part for turning the same, said head having a shank extending therefrom, an operating handle rigidly connected to said shank and extending outwardly therefrom, the outer end portion of the handle which is adapted to be grasped by the hand of the operator for turning the part being relatively wide and of spring metal and sufficiently thin as to flex within the hand of the operator when pressure is applied to the handle for turning the part whereby the extent of flexibility of the portion

grasped by the hand may be utilized for determining the approximate tightness of the part being turned.

4. A safety wrench comprising a head and a means adapted for engagement with a part for turning the same, said head having a shank extending therefrom, a relatively wide and thin operating handle rigidly connected to said shank, said handle being of spring metal and so dimensioned as to provide a decreasing cross-sectional area from the shank to the extreme outer end of the handle so that the outer end portion of the handle which is adapted to be grasped by the hand of the operator for turning the part is sufficiently thin as to flex within the hand of the operator when pressure is applied to the handle for turning the same whereby the extent of flexibility of the portion grasped by the hand may be utilized for determining the approximate tightness of the part being turned.

5. A safety wrench comprising a head and a means adapted for engagement with a part for turning the same, said head having a shank extending therefrom, an operating handle rigidly connected to said shank, said handle being of spring metal relatively flat in cross section and having longitudinal slots therein forming a tongue which is integral with the handle at the outer end thereof and which is free of the handle at its inner end; means shiftable on the handle longitudinally of the tongue and engageable with the tongue for varying the flexibility of the handle, the outer end portion of the handle which is grasped by the hand of the operator being flexible whereby the extent of flexibility of the portion grasped by the hand may be utilized for determining the approximate tightness of the part being turned.
